UNITED STATES PATENT OFFICE.

HENRY P. HILBERT, OF CINCINNATI, OHIO.

SLITTING AND WINDING MACHINE.

No. 874,070.

Specification of Letters Patent.

Patented Dec. 17, 1907.

Application filed August 3, 1907. Serial No. 386,891.

To all whom it may concern:

Be it known that I, HENRY P. HILBERT, a citizen of the United States, residing at Cincinnati, in the county of Hamilton and State 5 of Ohio, have invented certain new and useful Improvements in Slitting and Winding Machines, of which the following is a specification.

It is the object of my invention to provide 10 an improved slitting and winding machine in which the sheet to be slit and wound is introduced between cutters for slitting the sheet into lengths of suitable widths, the sheet being drawn through the cutters by 15 suitable drawing-rollers closely adjacent to the cutters, and wherein the strips may be wound in separated relation by suitable winding mechanism acting upon the combined strips from the center of the rolls being 20 wound and also selectively upon the surfaces of said separated rolls, for subjecting said separated rolls to combined rolling action from the center and also to separated rolling action at their peripheries, whereby the main 25 duty of the winding function is accomplished from the center and auxiliary differential winding action is imparted to the separated strip-rolls at their surfaces, so that all of the strip-units may be compactly rolled irrespec- 30 tive of differences in condition or thickness of material.

My improved device is especially applicable for slitting and rewinding various kinds of papers, whether plain, oiled or waxed.

35 In waxed papers an objection has heretofore been that the wax collected on the surface of the rollers, and another objection has been, in the manipulation of various kinds of papers, that electricity was generated, resulting in magnetism retarding or preventing 40 release between the paper and rollers, the tendency having been for the paper to follow the peripheries of the rollers in their rotation.

I prevent these objections by making one of 45 the drawing rollers of say iron or similar substance, and providing a scraper for scraping the surface of the wax that may accumulate thereon, and in providing the surface of the other roller with an electrically non-conducting covering, such as felt, thereby relieving 50 the tendency of the paper to cling to the surface of said rollers in their rotation.

The invention will be further readily understood from the following description and 55 claims, and from the drawings, in which latter:

Figure 1 represents a side elevation of my improved device, partly broken away. Fig. 2 is a plan view of the same. Fig. 3 is a perspective view of the winding end of the machine, partly broken away. Fig. 4 is a perspective view of one of the tubes for the surface-winding roller; and Fig. 5 is a similar view of one of the separating washers for the same.

1 represents the frame embracing the sides 3 4 tied together by suitable tie-rods 5 5'.

6 is a shaft arranged to support the unwinding roll 7 and held in releasable bearings 8, proper or usual means being provided for 70 properly braking the roll 7 or its shaft for placing the proper tension upon the web 9 which is adapted to be unrolled from the roll 7 and pass through the slitting mechanism for being slit into strips, the strips being then 75 separated and rewound upon a rewinding roll. The shaft 6 has a collar 10 fast thereon. A friction-band 11 is received about this collar, a set-screw 12, passing through ears 13, adjusting the frictional resistance 80 thereof. The band 11 is arranged to strike pins 14 on the frame for arresting the rotation of the band and applying the frictional resistance thereof to the collar. The collar has an annular groove 15 which receives a yoke 16 of the bell-crank lever 17 pivoted on a bolt 18 to a bracket 19 on the frame, a screw-rod 20 threading into a swivel-nut 21 on the lever. The screw-rod is suitably journaled in the frame and extends to 90 the delivery end of the machine, where it is provided with a hand-wheel 22 for its manipulation.

23 24 and 25 are suitable tension and smoothing rollers for the web and are adapted to run idle and to have more or less resistance applied thereto in suitable manner, not particularly described because well-known.

26 27 are knife-shafts journaled at their 100 ends respectively in boxes 28 supported in slide-ways 29. These shafts respectively have knives 32 33 adjustably secured thereto in such manner that the knives may be positioned lengthwise of the shafts for cutting 105 the web into strips of suitable widths.

37 38 are the drawing-rollers and are positioned closely adjacent the cutters for drawing the paper through the cutters, the effect being that the drawing action takes place 110 only upon a short length of the cut strips, thereby minimizing the danger of tearing the

strips. The drawing-roller 38 has a shaft 39 journaled in boxes 40 supported in the slide-ways 41 of the housing 42. This roller is preferably a metal roller, for instance iron, 5 against the periphery of which a scraper 43 acts to scrape the wax which may be received upon the roller from the paper, so as to keep the roller clean. This scraper is preferably secured to a rock-shaft 44 in bearings 45 on the housing, the scraping edge being pressed against the roller and the scraper held in place by set-screws 46 passing through the bearings against the rock-shaft. 10 The drawing-roller 37 is supported on a shaft 50 supported at its respective ends in boxes 51, each of which has an upward extension 52 in which there is a slot 53 for receiving a shaft 54 extending transversely of the machine, the said shaft at each end having 15 an eccentric journal 55 journaled in a bearing-block 56 secured to the upper end of the housing. At its outer end the shaft 54 has a hand-wheel 57 for turning the shaft and thereby raising or lowering the boxes for adjusting the elevation of the drawing-roller 37. After adjustment the shaft may be clamped in adjusted position by the set-screw 58. This roller 37 has a covering 59 of electrically non-conducting material, such as 20 felt, so that in the operation of the machine magnetism may not be created or induced between the drawing-rollers, and insuring that the paper-strips shall readily release from the drawing-rollers to prevent tearing 25 of the same. The cut strips are then directed about the rollers 60 61, the roller 61 being journaled at the upper ends of arms 62 extending upwardly from the housing. The strips are further directed about the rollers 30 63 64 and are then wound about the winding-arbor 65, for forming the rewinding roll 66, but prior to reaching the roller 63 a separator-roller 67 is caused to act upon the strips in the stretch between the roller 61 and 35 the roller 63 for separating the strips so that they may be wound about the winding-shaft or arbor in separated relation for forming distinct rolls 68 of narrow strips which may be readily removed without the necessity of 40 chopping them apart when removing them and insuring that the rolled strips may be unwound without having the edges of the strips crushed or mingling with each other. 45 The separator-roller 67 preferably comprises short sections 70 of tubes separated by washers 71 of greater diameter than the tubes and suitably positioned end for end upon the shaft as by collars 72. The tubes and washers are preferably of metal and sufficiently loose upon the shaft to permit their 50 turning upon the shaft if undue stress or friction be applied at their peripheries. 55 The winding-shaft is arranged to be suitably driven as will be hereinafter more particularly explained, for acting collectively

from the center of the strips being wound about the shaft. For acting separately upon the strips from their surfaces a surface-winding roller 76 is also provided. This surface-winding roller, similarly to the separator-roller 67, acts as a separator-roller, being similarly constructed, as by being provided with separator-tubes 77 having washers 78 therebetween suitably positioned similar to the tubes and washers of the separator-roller 67, as by collars 79, the tubes and washers being sufficiently loose upon the shaft to permit their turning upon the shaft if undue stress or friction be exerted at their peripheries. Separator tubes of different lengths 80 may be provided for strips of different widths. 75

The driving mechanism of my improved device will now be described. A prime-mover is shown as a pulley 81 which rotates 85 loosely on a stud 82 secured to the frame and forms one member of a friction-clutch 83, the other member 84 of which also rotates loosely about the stud 82 and has a pinion 85 thereon. 86 is a collar, also on the stud 82. A 90 lever 87 has a fork 88 taking about the collar and is articulated with the collar by pins 89. The lever 87 is pivoted at 90 on a bracket 91 and has a threaded nut 92 swiveled thereon, an adjusting screw 94 being threaded into 95 said nut 92 and having a handle 95, for positioning the lever 87 and controlling the frictional engagement in the clutch 83, the adjusting screw 94 being journaled in bearings 96 on a bracket 97 on the frame. There is a 100 ball-bearing 98 between the collar 86 and the pulley 81 and a ball-bearing 99 between the clutch-member 84 and the frame of the machine. The friction-clutch 83 forms the initial-drive for the machine. There is a second friction-clutch 101, which is a driven friction-clutch, and is operated from the friction-clutch 83 and has for its purpose the operation of the central winding-shaft. The friction-clutch 101 comprises the members 110 102, 103, the member 102 having a pinion 104 thereon and the member 103 having a gear 105 thereon. These members are journaled about a stud 106 secured to the machine. 107 is a compression-collar for the 115 clutch 101 and is threaded on a threaded extension 108 of the stud 106. There is a collar 110 splined to the stud 106, as shown at 111, which forms an end-thrust member of a ball-bearing 112. A spring 113 is between 120 the collars 110 and 107, the tension of which is arranged to be adjusted by the compression-collar 107 for adjusting the degree of frictional contact in the friction-clutch 101. There is a ball-bearing 114 between the friction-clutch 101 and the frame. A pinion 115 125 meshes the gear 105 and is journaled on a stud 116 on the frame and in turn meshes a gear 117 on the stub 65' of the winding-shaft 65 for operating the latter. The winding- 130

shaft is arranged to be clutched to the stub 65' by a clutch 118 and the winding-shaft and stub are respectively journaled in releasable bearings 119 119' in the frame. The 5 clutch-member 102 forms a brake-member for the friction-clutch 101 for providing retarding action in the winding roll when this is desired. Thus 120 is a brake having a 10 brake-shoe 121 and a lever 122 for operating the same and arranged to force the shoe against the rim of the friction-member 102.

Gear transmission is effected between the friction-clutches by means of a gear 125 which meshes with the pinion 85 on the 15 clutch-member 84, a gear 126 meshing the gear 125, and a gear 127 meshing the gear 126 and the pinion 104 on the friction-member 102. The gears 125 and 127 are respectively journaled on studs 128 and 130 suitably secured to the frame of the machine, the gear 126 being on a shaft 129.

The surface-winding roller is supported and driven as follows: 135 is a jointed rocker-frame comprising the bell-crank member 136 25 and the link-member 137, hinged together on a swinging tie-rod 138, and rocking on the tie-rod 5' which connects the sides of the machine-frame. The member 136 comprises the side-arms 139 140 whose outer ends are 30 connected by a tie-rod 141 upon which suitable weights 142 are adapted to be supported for normally swinging the surface-winding roller toward the roll being wound. The member 137 comprises the side-arms 143 144 35 having bearings 145 146 for the reduced ends 147 of the surface-winding shaft, these reduced ends forming studs received by slots 148 in arms 149 on the machine-frame, the slots preferably being radial of the center- 40 winding shaft. As the diameter of the roll being wound increases the surface-winding roller is forced outwardly, guided by the slots, against the resistance of the weights 142. Rotary motion is also communicated 45 to the surface-winding roller 76, which I accomplish by a train of gearing preferably having the same source of power as the gears for the center-winding shaft and preferably so arranged that the surface-winding roller 50 may be continually driven irrespective of the diameters which the rewinding roll may attain. Thus 151 is a gear secured to the shaft 129 for rotating therewith. The gear 151 meshes with a gear 152 journaled on a stud 55 153 secured to the machine-frame and in turn meshes with a gear 154 having a rotary axis coincident with the rocking-axis of the rocker-frame 135, being journaled on the tie-rod 5'.

60 The arms 139 and 143 are preferably the gear-supporting arms of the jointed rocker-frame. A gear 155 meshes with the gear 154 and a gear 156 meshes with the gear 155, the gears 155 and 156 being journaled on studs 65 157 158 secured to the arm 139. Gears 159

and 160 are secured together and journaled on the tie-rod 138 which forms the articulation between the members of the rocker-frame. The gears 159 and 160 rotate together, the gear 159 being meshed by the gear 156 and the gear 160 meshing with a pinion 162 journaled on a stud 163 secured to the arm 143. A gear 164 meshes with the pinion 162 and is secured to the surface-winding shaft for operating the latter. In 75 this manner a uniform speed is imparted to the surface-winding roller irrespective of the diameter of the roll being wound, the respective tubes of the surface-winding roller being sufficiently loose upon the surface-winding 80 shaft to permit turning thereon and exerting frictional driving contact between the surface of the winding roller and the periphery of the roll being wound for exerting differential winding action upon the various narrow-striped rolls being wound, the washers also acting to maintain the various strip-rolls in separated relation, the center-winding shaft meanwhile acting to collectively wind all of the strip-rolls and performing the main 90 duty of the winding, leaving the surface-winding sectional roller to act as an auxiliary surface-winding roller acting to differentially take care of the differences in compactness of the separate strip-rolls, the combined action 95 of the center and surface-winding effect being to compact the several strip-rolls in the winding action.

In operation, the speed of the center-winding shaft is fastest at the beginning of the 100 winding of the roll, as the roll is then of smallest diameter. As the roll increases in diameter its weight also increases thereby requiring greater driving force to drive it, which will partially determine its peripheral 105 speed, its peripheral speed being also determined by the adjustment of the friction-clutch 101 by means of the compression-collar 107. In practice it is necessary to supply greater frictional contact as the diameter 110 of the rewinding roll increases for maintaining a given peripheral speed. The surface-winding roller rotates in the direction opposite to the direction of rotation of the center-winding arbor, as indicated by the arrows 115 a b, and the speed of the surface-winding tubes is preferably greater than the peripheral speed of the roll being wound so as to selectively crowd the various strips upon the roll being wound, but, while the surface-winding tubes operate with faster peripheral 120 speed than the peripheral speed of the roll being wound, their frictional power is preferably not sufficiently great to substantially overhaul the center-winding shaft. The 125 surface-winding roller acts as a surface-winding auxiliary to the center-winding and aids in drawing the separated strips about the center-winding arbor and thereby prevents the full stress of the center-winding being ex- 130

erted throughout the bulk of the roll being wound, which is composed of the separated strips. It relieves the tension upon those separated strips, which tension would otherwise be exerted throughout the full length of the strips between the drawing roller and the center arbor. It acts intermediately of those points for aiding in drawing the separated strips about the central arbor, in other words, acts upon the surface of the strips to the extent to which they have been wound for taking care of that portion of the strips already wound into the roll, and relieves that portion of pulling stress from the stretches of the strips between the auxiliary surface-winding roller and the drawing rollers and thereby insures that the tension of all the strips in their stretches between the surface-winding roller and the drawing rollers shall be substantially equal, thereby preventing undue stress on any one of the separate strips for preventing tearing of the strips.

For driving the drawing rollers and the knife-shafts, I provide the lower drawing-roller shaft with a gear 167 which meshes the pinion 85. The upper drawing-roller is driven by frictional contact with the paper and lower roller. There is a second gear 168 on the lower drawing-roller shaft which meshes with a pinion 169 journaled on a stud 170 secured to the machine-frame and in turn meshes a gear 171 on the lower knife-shaft, the latter gear in turn meshing with a gear 172 on the upper knife-shaft for causing the knives to rotate in unison.

If desired the separated strips may have their ends secured to and be wound about cops 173 separated by washers 174, the cops and washers being firmly secured to the rewinding shaft 65 by being clamped between a collar 175 and a nut 176 threaded on the rewinding shaft.

Having thus fully described my invention 45 what I claim as new and desire by Letters Patent is:

1. In a slitting and winding machine, the combination with knives and drawing-rollers, of a center-winding shaft and power means for turning the same, and a surface-winding roller and power means for turning the same, for combinedly acting upon the roll being wound simultaneously from its center and its surface, and means for permitting said surface-winding roller to recede automatically from said center-winding shaft as the diameter of the roll being wound increases, substantially as described.

2. In a slitting and winding machine, the combination with the cutters and means for turning the same, of drawing rollers and combined center-winding and surface-winding devices for winding the cut strips, and a common shaft and gearing driven thereby for driving said drawing rollers and center-wind-

ing and surface-winding devices from a common source of power, substantially as described.

3. In a slitting and winding machine, the combination with slitting mechanism and drawing-rollers, of a center-winding shaft having a friction-drive, a surface-winding roller, a jointed rocker-frame for supporting said surface-winding roller and gearing on the respective limbs of said rocker-frame for driving said surface-winding roller, substantially as described.

4. In a slitting and winding machine, the combination with the cutters, of a center-winding arbor and means for driving the same for acting combinedly on the strip-rolls being wound from the inside thereof, and a surface-winding roller and means for driving the same, said surface-winding roller comprising relatively rotatable tubes and separator-flanges for differentiatingly acting on the surfaces of the separated strip-rolls, substantially as described.

5. In a slitting and winding machine, the combination with the slitting mechanism and means for supporting and driving the rewinding roll from its center, and a driven surface-winding roller yieldingly held against the rewinding roll, and means for permitting said surface-winding roller to recede from the axis of said rewinding roll as the diameter of said rewinding roll increases, substantially as described.

6. In a slitting and winding machine, the combination with slitting mechanism, of a driven center-winding arbor and a driven surface-winding roller, of means for yieldingly holding said surface-winding roller against the roll being wound with a pressure independent of the weight of said roll being wound and permitting retreat of said surface-winding roller from said central arbor as the diameter of the roll being wound increases, substantially as described.

7. In a slitting and winding machine, the combination with slitting mechanism, of a center-winding arbor and a surface-winding roller, means for driving said center-winding arbor comprising a friction-clutch having a yielding clutch-member, means for regulating the yield of said clutch-member, means for rotating said surface-winding roller in the direction opposite to the direction of rotation of said center-winding arbor and at a peripheral speed greater than the peripheral speed imparted by said center-winding arbor to the periphery of the roll being wound, and means for yieldingly holding said surface-winding roller against the roll being wound and permitting retreat of said surface-winding roller from said center-winding arbor as the diameter of the roll being wound increases, substantially as described.

8. In a slitting and winding machine, the combination with slitting mechanism, of a

driven center-winding arbor, a driven surface-winding roller, a prime-mover comprising a friction-clutch, means for regulating the friction-contact in said clutch, a driven 5 friction-clutch for the center-winding arbor, means for permitting yield of one of the members of said last-named friction-clutch, means for regulating said yield, gearing between said last-named friction-clutch and 10 said center-winding arbor, a train of gears connecting said friction-clutches, gearing connecting with said train of gearing and said surface-winding roller, a jointed rocker-frame comprising limbs, on one of which 15 limbs said surface-winding roller is journaled, said last-named gearing comprising a train of gears the members whereof are journaled on said respective limbs and have meshing engagement throughout the movements of said limbs, substantially as described. 20

9. In a slitting and winding machine, the combination with slitting mechanism, of a pivoted rocker-frame comprising limbs, a 25 driven surface-winding roller journaled in one of said limbs, parts having radial slots by which said surface-winding roller is guided, means for driving said surface-winding roller, and means for yieldingly urging said surface- 30 winding roller toward the axis of the roll being wound.

10. In a slitting and winding machine, the combination of slitting knives, drawing rollers closely adjacent thereto for drawing the 35 web through said slitting knives, a driven center-winding arbor, tension means between said arbor and the drawing rollers for forming a stretch between said arbor and drawing rollers of the strips being wound, a 40 separator-roller acting on said stretch and comprising separators and tubes therebetween, a driven surface-winding roller and means for yieldingly urging surface-winding roller toward said center-winding arbor, substantially as described. 45

11. In a winding machine, the combination of a center-winding arbor, means for driving the same, an articulated rocker-frame having limbs, a surface-winding roller 50 supported on one of said limbs, means for guiding said surface-winding roller, means for yieldingly urging said surface-winding roller toward said center-winding arbor, and means for driving said surface-winding roller, substantially as described. 55

12. In a winding machine, the combination of a center-winding arbor, means for driving the same, an articulated rocker-frame, a surface-winding roller journaled 60 therein, means for yieldingly urging said surface-winding roller toward said center winding arbor, and means for driving said surface-winding roller, said surface-winding roller comprising tubes arranged end for end of the 65 roller and capable of relative rotary motion

thereon, said surface-winding roller also comprising strip-separators, substantially as described.

13. In a winding machine, the combination of a center-winding arbor, a rocker-frame comprising limbs articulated together, a surface-winding roller journaled in one of said limbs, and a train of gears supported on said respective limbs for driving said surface-winding roller, said rocker-frame being permitted to yield against resistance for urging said surface-winding roller toward said center-winding arbor, substantially as described. 70

14. In a winding machine, the combination of a center-winding arbor, a rocker-frame comprising limbs articulated together, a surface-winding roller journaled in one of said limbs, and a train of gears supported on said respective limbs for driving said surface-winding roller, said rocker-frame being 80 permitted to yield against resistance for urging said surface-winding roller toward said center-winding arbor, said surface-winding roller comprising strip-separators and surface-winding tubes arranged end for 85 end thereon and capable of relative rotary motion, substantially as described. 90

15. In a slitting and winding machine, the combination of slitting knives, drawing rollers closely adjacent thereto for drawing the 95 web through said slitting knives, a driven center-winding arbor, tension means between said latter arbor and the drawing rollers for forming stretch of the strips being wound between said arbor and drawing rollers, a driven surface-winding roller acting on the peripheries of the strip-rolls and rotating in the direction opposite to the direction of rotation of said center-winding arbor, said surface-winding roller comprising strip-separators and relatively rotatable surface-winding tubes arranged end for end therebetween, means for yieldingly urging said surface-winding roller toward said center-winding arbor, and a separator-roller acting on 100 105 said stretch between said surface-winding roller and drawing rollers, substantially as described. 110

16. In a slitting and winding machine, the combination of slitting knives, drawing rollers closely adjacent thereto for drawing the web through said slitting knives, a driven center-winding arbor, tension means between said latter arbor and the drawing rollers for forming a stretch of the strips being wound 115 between said arbor and drawing rollers, a driven surface-winding roller acting on the peripheries of the strip-rolls and rotating in the direction opposite to the direction of rotation of said center-winding arbor, a separator 120 roller acting on said stretch between said surface-winding roller and said drawing rollers, said surface-winding roller comprising strip-separators and relatively rotatable surface-winding tubes arranged end for end 125 130

therebetween, and a rocker-frame, said surface-winding roller supported on said rocker-frame, said rocker-frame being permitted to swing for yieldingly urging said surface-winding roller toward said center-winding arbor, substantially as described.

17. In a slitting and winding machine, the combination with slitting knives, drawing rollers comprising a metal roller and an opposing felt-covered roller, a scraper having a scraping edge impinging said metal roller, said drawing rollers being closely adjacent to said slitting knives for drawing the web through said slitting knives, a driven center-
10 winding arbor, tension means between said arbor and the drawing rollers for forming a
15

stretch between said arbor and drawing rollers of the strips being wound, a driven surface-winding roller, said surface-winding roller comprising separators and relatively 20 rotatable tubes, and means for yieldingly urging said surface-winding roller toward said center-winding arbor, substantially as described.

In testimony whereof I have subscribed 25 my name hereto in the presence of two subscribing witnesses.

HENRY P. HILBERT.
